UNITED STATES PATENT OFFICE.

MAXIMILIAN GERCKE, OF PASING, NEAR MUNICH, GERMANY.

DISTILLATION OF BITUMINOUS MATERIAL.

Application filed April 21, 1921. Serial No. 463,382.

To all whom it may concern:

Be it known that I, MAXIMILIAN GERCKE, a citizen of the State of Prussia, Germany, residing at Pasing, near Munich, Bavaria, 5 Germany, have invented certain new and useful Improvements in the Distillation of Bituminous Material, of which the following is a specification.

This invention relates to the distillation 10 of bituminous material and more especially bituminous coal, bituminous brown coal or bituminous schist or shale. Fuels that are rich in bitumen and ammonia are distilled by the action of heat, in retorts, retort-generators and similar contrivances, in order to recover tar, oils and ammonia. The lower the temperature and the higher the pressure applied, the more fluid products obtained; and the higher the temperature and the 15 lower the pressure used, the more gases given off in the operation. The distillates obtained at the lowest temperatures and the highest pressures are of special value. In Mond gas generators, in order to recover 20 the greatest possible amount of ammonia compounds and tar that come over at low heat, the temperature of gasification is kept at the lowest possible point by blowing in large quantities of steam at atmospheric 25 pressure. In other systems the same end is attained by means of generators, and when the gasification is effected in retorts the result is got by drawing off the products of 30 gasification at the point where they arise, in such manner that these products are kept 35 from contact with hot parts of the gasifying plant.

According to another well known process 40 steam is introduced into vertical retorts used for the distillation of brown coal, through a distributing pipe fitted on the wall of the retort which is heated externally. The steam enters into the path of the fuel which sinks down before it and becomes 45 superheated to a greater and greater degree through heat taken up from the glowing walls of the retort, due to the increasing temperature as the bottom is approached. In these well known processes of 50 distilling coal and shale in open slow combustion furnaces, heated by the external action of direct fire, it is impossible to regulate exactly the temperature and pressure of

the steam admitted, and the speed at which the fuel passes through the plant. 55

The subject of my invention is a process by which the most valuable by-products resulting from the gasification of the fuel treated (bituminous coal, bituminous shale, or bituminous brown coal) are extracted in 60 a continuous operation, by the action upon the fuel of a current of superheated steam of adjustable temperature and pressure, in such a manner that the fuel and the by-products separated from it are not exposed to 65 any higher temperature than that of the superheated steam used.

Figs. 1 and 2 of the drawings are dia- 70 grammatic representations of two forms of apparatus for carrying out the new process. 70 Figs. 3 and 4 are cross-sections through the distilling chamber.

In Fig. 1 A indicates the distilling cham- 75 ber, constructed as a tubular boiler. B are charging sections and C discharging sections. D are double walled tubes disposed within the chamber and provided on the upper side with a large number of perforations to admit superheated steam. The tubes are centred against the chamber shell 80 and suitably supported. Endless conveyor chains E are arranged to pass through the tubes D. The links or members of the chain are formed as steam pistons F, F¹, F², F³, etc., which are rendered fluid tight against 85 the cylindrical walls of the charging and discharging sections B and C by labyrinth packings. As the piston members of the chain are all of the same diameter and are rigidly connected one with another they are 90 all subjected to the same pressure irrespec- 90 tive of position. The tractive effort on the pistons is transmitted through the chain.

The fuel to be distilled is first comminuted and prepared for use. It is then fed into 95 a hopper G from which it is delivered at H into the spaces between the pistons of the conveyor chain. Thence it is carried into the charging sections B, where it is preheated to the temperature of the saturated steam used 100 in distilling. The sections B are surrounded by a steam jacket b, the steam entering at c and leaving at d. Thereafter the fuel passes through the tubes D, in which superheated steam plays around it on all sides. The 105 steam passes into the chamber A through a

connection J and flows out again through a pipe J¹ after it has given up its superheat to the fuel and has separated the by-products contained in the latter. The liquid by-products and the water of condensation flow off from the tubes D, as the drawing shows, at the lower end of the chamber A into a collecting vessel K in which the gas-liquor is collected, whilst the vapors and gaseous portions flow off with the steam.

The fuel from which the by-products have thus been separated leaves the distilling chamber A through the discharge connections C and is removed from the conveyor 15 by the upper chain wheel L and deposited into a bunker M, ready for subsequent use.

The by-products which are separated in the well-known manner from the gas-liquor and the steam, are subjected to further 20 treatment as required.

In the form of apparatus shown in Fig. 1 the steam used in distilling is kept in continuous circulation through the distilling chamber A, the gas-liquor collector K, and 25 a steam superheater P, by means of a steam blower, the object being to increase the quantity of by-products in the distilling steam and the gas-liquor.

N is the steam boiler for working the 30 steam jet blower O, and P is the steam superheater. Q is the combustion space of the steam boiler and R is a feed water heater, utilizing the waste heat from the steam boiler.

35 The regulation of the steam temperature required for extracting and distilling the fuel and the regulation of the pressure are effected by well-known means common to steam boilers.

40 Another form of the process forming the subject of my invention is one in which the hygroscopic water contained in the fuel to be treated for the recovery of primary tar is evaporated in the first place by the 45 direct action of an oil bath, consisting of heavy hydrocarbons with a high boiling point, and in which the fuel, or rather the remaining dry mass is afterwards distilled by means of superheated steam in the manner already described, to obtain primary tar or coal oil.

45 In this form of the process a circulating oil bath, having a high boiling point and consisting of heavy anthracene oil, or any fraction of coal oil or brown coal oil having a high boiling point, or any other residual oil of low value, acts firstly merely as an external heating agent of the fuel that is forced into it. It drives off the water and 55 the volatile constituents of the fuel that have a boiling point below its own temperature. In the operation the oil penetrates into the pores of the fuel as the latter is gradually freed from water and saturates the dry mass. 60 As the fuel rises up out of the oil bath a

portion of the oil trickles off, whilst the oil absorbed by the pores of the fuel, along with the pitch dissolved in it, adheres to the fuel as an impregnating mass and the whole is then exposed to the action of the 70 superheated steam. All the volatile constituents of the fuel and of the oil absorbed by it that gasifies at a point below the highest temperature of the superheated steam used are thus driven off, and the extracted fuel, also the non-volatile residue of the oil, particularly the pitch, remain as a sort of half-coke and are discharged in that state at the conclusion of the process. Of the vapours driven off, the oil used for 80 the oil bath is, of course, the portion with the highest boiling point and consequently it is the first to be deposited in the fractional condensation of the extracted matters. It can be returned into the oil bath, unless 85 it is preferred always to use new waste crude oil and to refine it for the recovery of the more valuable fractions, using the process herein described. The residue consisting of pitch and impurities, can be used 90 to saturate the fuel and to increase the caloric value of the dry extracted mass.

95 As will be understood from the foregoing remarks, the saturation of the fuel with oil from the oil bath takes place first, and thereafter the distillation with superheated steam is effected resulting in that portion of the oil used for saturation which is volatile at the temperature adopted for the distillation being driven off again.

100 The apparatus used in this modified form of the process is shown diagrammatically in Fig. 2 and, as will be seen, in its essentials it is the same as the apparatus shown in Fig. 1.

105 One difference, however, is that the tubular boiler is divided into a part N¹, supplied with water, and a part N², supplied with oil having a high boiling point. The steam superheater P¹ is arranged between 110 these two. The collecting vessel K¹ for the separation of the impurities, etc., that are carried over, is connected with the part N² of the boiler and with the distilling chamber A by pipes in such manner that an oil bath 115 is formed in the lower portion of chamber A through which the conveyor chain E passes carrying with it the fuel that is constantly fed forward between the pistons F¹, F², F³, etc. By means of a centrifugal pump 120 S fitted in the piping, the oil bath is kept in continuous circulation through the collector K¹, the tubular boiler N² and the lower portion of the distilling chamber A. The boiler N² is heated by the waste gases from 125 the combustion space of the tubular boiler N¹ and by the steam superheater P¹. The oil bath takes up heat from the hot gases and transfers it to the fuel. The fuel is thus preheated to the temperature of the oil and 130

any water that may be present is evaporated in the oil bath. The fuel thus freed from water is conveyed through the oil bath by the conveyor chain and is then distilled for 5 primary tar or coal tar by superheated steam from the boiler N^1 and superheater P^1 in the manner already described in connection with the apparatus shown in Fig. 1. The aqueous vapours separated from the oil bath, 10 originating from the water contained in the fuel, mix with the steam used for distilling and with the hydrocarbon vapours that are distilled over and pass away to enter into fresh combinations. The steam used for the 15 distillation as well as the gaseous and vapor-like products of distillation are discharged through a conduit indicated at J^2 . Any loss of oil from the oil bath as by leakage past the packings of the pistons F^1 , F^2 , F^3 , etc. is 20 made good by pumping in oil of a high boiling point. The oil that has taken up impurities while being used is collected in a receiver as shown in the drawing and after purification it can be utilized again.

25 A special advantage of this particular form of the process is that brown coal of very little value is not only distilled for tar but also has its caloric value considerably improved by partial saturation with heavy 30 anthracene oils, so that its value in use increases and the field of its utility is enlarged. Further, the heavy tar oil that is unsuitable for driving Diesel or other oil engines can be used for firing in conjunction with brown 35 coal, thus avoiding the use of special oil firing arrangements which would otherwise be necessary.

I claim:—

40 1. A process for distilling bituminous material which consists in positively and continuously moving the material along and during such movement subjecting it in a closed chamber, without the use of external heat, to the action of superheated steam in a 45 circulation and controllable as to temperature and pressure.

45 2. The process as specified in claim 1 which comprises also the step of preheating the bituminous material prior to subjecting it to the action of the superheated steam.

50 3. The process as specified in claim 1, which comprises the step of passing the material to be treated through a bath of hot

circulating oil thereby preheating the material and at the same time saturating it with the oil. 55

4. A distillation plant comprising a distillation chamber, a tubular passage having perforated walls extending through said chamber, an endless piston chain conveyor 60 adapted to pass through said tubular passage in an axial direction, and means for generating superheated steam and feeding it through said chamber.

5. A distillation plant comprising a distillation chamber, a tubular passage having perforated walls extending through said chamber, an endless piston chain conveyor adapted to pass through said tubular passage in an axial direction, means for generating superheated steam and feeding it through said chamber, and a vessel connected with said chamber for collecting gas liquor. 65 70

6. A distillation plant comprising a distillation chamber, a tubular passage having perforated walls extending through said chamber, an endless piston chain conveyor adapted to pass through said tubular passage in an axial direction, means for generating superheated steam and feeding it through said chamber, and means for heating oil and causing said hot oil to circulate also through said chamber. 75 80

7. A distillation plant comprising a distillation chamber, a tubular passage having perforated walls extending through said chamber, an endless piston chain conveyor adapted to pass through said tubular passage in an axial direction, means for generating superheated steam and feeding it through said chamber, and means for heating oil with the waste gases of said steam generator and causing said hot oil to circulate also through said chamber. 85 90 95

8. A distillation plant comprising a distillation chamber, a tubular passage with perforated walls extending through said chamber, an endless piston chain conveyor adapted to pass through said tubular passage, an oil bath surrounding the lower part of said tubular passage, and means for causing superheated steam to pass through the space above said oil bath. 100

In testimony whereof I affix my signature.
MAXIMILIAN GERCKE.
